CONTAINER FOR LIQUIDS AND
SEMILIQUIDS

Harold Gar Vaughn, Warren, Ohio, assignor to
The Ohio Corrugating Company, Warren, Ohio,
a corporation of Ohio

Application March 23, 1951, Serial No. 217,100

8 Claims. (Cl. 222—539)

1

This invention relates to containers for liquids and/or semi-liquids, more particularly to the closure therefor wherein means are provided for insuring sealing when the container is filled with a suitable material, so that the container may be handled and shipped to the user devoid of danger of leakage and unauthorized tampering with the container contents.

In containers, of which I have knowledge, various forms of sealing devices have been employed; for example, (I) a section of flexible wire was threaded through embossments or lugs on the closing cap or screw threaded plug and one or more lugs fixed to the container wall, bung ring thereon or other part of the container, the ends of the wire being secured together by a lead slug, which arrangement (a) involved extra labor and expense and in many instances prevented storing of the containers in stacked relation, and (b) was employed solely to prevent an unauthorized person from gaining access to the container contents and (II) the closing cap or screw threaded plug was enclosed by a cup-shaped member, capable of being deformed to detect tampering therewith, in which arrangement the periphery of the cup-shaped member was exposed and capable of being engaged by a tool (such as a screw driver) and pried off and replaced in a manner that avoided detection.

The sealing means herein disclosed includes a pair of members having interrelated annular sealing walls effective to prevent leakage.

This invention comprises a seal for a container to prevent leakage of material therefrom, one member of the seal consisting of a member requiring deformation to gain access to the container; accordingly, access to the container or tampering with the seal by an unauthorized person is readily detected.

The invention also includes a construction having a combined sealing and detectable member and a closure device arranged to protect the member against damage during handling and shipment of the container. The invention also includes a sealing means within an outer or exterior closure member and incorporated with and providing a gasket seat for a reversible spout, whereby the discharge opening around the spout is sealed when the latter is in an operative or pouring position.

One object of the invention is to provide an improved closure having therewithin means which seal the container and detect unauthorized access thereto.

Another object of the invention is to provide an improved container closure having a sealing and deformable means and a closure member the walls of which are arranged to protect the sealing and deformable means against damage due to handling and shipping of the container.

2

Another object of the invention is to provide an improved container sealing means consisting of a pair of members having annular, complementary walls disposed in fixed relation.

Another object of the invention is to provide an improved sealing means for the discharge opening of a container and consisting of a member having an embossed annulus and a removable deformable disk the periphery of which is provided with an annular wall complementary to and seated in the annulus and adapted to seal the container, the outer side wall of the annulus extending outwardly of said annular wall to prevent tampering with the latter.

Another object of the invention is to provide an improved combined closure and sealing means for the discharge opening of a container, wherein one element of the sealing means is provided with a wall forming a seat for a spout.

Another object of the invention is to provide an improved sealed closure and discharge means for the discharge opening of a container, consisting of a collar mounted in said opening, a reversible spout, a support within the collar for the spout when the latter is in non-pouring or pouring position, an annular closure device for securing the spout on the support and a removable deformable disk for closing said collar when the spout is in non-pouring position, the marginal portion of the disk and collar having interrelated annular walls to provide a leak-proof and tamper-proof seal for the discharge opening.

A further object of the invention is to provide an improved combined sealing and detachable means for the discharge opening of a container of simple and economical construction and capable of being readily positioned.

Other objects of the invention will be apparent to those skilled in the art to which my invention relates from the following description taken in connection with the accompanying drawings, wherein

Fig. 1 is a fragmentary view showing in section on the line 1—1 of Fig. 2 a portion of a container and a closure therefor embodying my invention;

Fig. 2 is a fragmentary plan view on the line 2—2 of Fig. 1;

Fig. 3 is a plan view, parts being broken away; taken on the line 3—3 of Fig. 4a;

Fig. 4 is a view similar to Fig. 1, but showing a modified form of construction;

Fig. 4a is a view similar to Fig. 1, somewhat enlarged, but showing in section the modified form of construction, the parts being in the position they occupy when the container is filled ready for shipment to a user;

Fig. 4b is a section similar to Fig. 4a, but showing the spout in pouring position and the cap 60 therefor removed;

3

Fig. 5 is a fragmentary section of parts shown in Fig. 4a, enlarged;

Fig. 6 is a sectional view similar to Fig. 4a, but showing another modified form of construction;

Fig. 7 is a fragmentary plan view on the line 1—1 of Fig. 6, parts being broken away; and

Fig. 8 is a fragmentary section of the parts shown in Figs. 6 and 7, but showing the spout in pouring position.

In the drawings, referring to Figs. 1, 2 and 3, 1 indicates as an entirety a container comprising a body having a side wall 1' (preferably of cylindrical shape in cross section) and a top or head 2, which may be permanently secured to the side wall 1' by welding, soldering, double seaming or otherwise; but in the construction shown for illustrative purposes the side wall 1' is provided with a false bead 1a and the top 2 has a peripheral flange 2' engaging a suitable gasket 2x and terminating in lugs 3 which are bent by hand, a suitable tool or a machine inwardly around, into engagement with and under the false bead, with the gasket 2x between the flange and bead, to seal and removably secure the top in position.

The top 2 is formed with an emptying or discharge opening 2a, in which the inner end of a collar 4 is fixedly mounted (as later set forth), adjacent the flange 2' at one side of the top 2. By preference that portion of the top wall in which the collar 4 is mounted is embossed downwardly and outwardly, as shown at 2b, so that the axis of the collar 4 extends at a right angle to the wall 2b to facilitate pouring of the container contents.

This arrangement enables the closure parts, when the latter are in the position they occupy after the container is filled ready for shipment, to be below or within the plane of the top flange 2', as shown in Fig. 1. By preference, the inner end of the collar is provided with a flange 4a, which and the marginal wall of the opening 2a are interconnected in fixed relation in a well known manner. The side wall of the collar 4 is embossed to provide screw threads 4b, which are engaged by the screw threaded side wall of an annular closure device 5. The upper end of the collar is provided with an inwardly extending annulus 6 the intermediate portion of which, throughout its circumference, is embossed to form a recess 6a of U-shape in cross section. The outer side 6' of the recess 6a is preferably somewhat longer than the inner side thereof, to dispose the recess below the top of the collar, for a purpose later set forth. The inner side 6b of the recess 6a is extended throughout its circumference parallelly to the embossed wall 2b, as shown at 6b' and serves to reinforce the walls of the recess 6a.

8 indicates a combined sealing and detectable member consisting of a removable disk formed of relatively thin resilient material and capable of being deformed. The member 8 is provided with a peripheral depending flange 8a terminating in an annular sealing element 8b of U-shape in cross section complementary to the sides and bottom of and seated in the recess 6a, to provide a seal therebetween and prevent leakage from the container through the collar 4.

The walls of the sealing element 8b have a pressed-in engagement with the side and bottom walls of the recess 6a and are therefore secured in fixed face-to-face relation to the walls of the recess 6a to effect a tamper-proof and leak-proof

seal without the use of a gasket, and as the side wall 6' of the recess 6a extends outwardly beyond the sealing element 8b, the outer peripheral edge of the latter cannot be engaged by a pointed tool or other device and pried out, except by deforming the element 8b and/or the member 8, the effect of which is to indicate access to the container. As shown, the top wall 5a of the annular closure device 5 extends inwardly beyond the annular sealing element 8b, its inner marginal portion being embossed inwardly, as shown at 5b, which embossed portion is arranged to engage the sealing member 8 under pressure when the closure device 5 is threaded on the collar 4 and tightened in position. It will be observed that when the closure device 5 is in tightened position, its top wall 5a, outwardly of the marginal portion 5b, is spaced from the upper end of the collar 4 and the U-shaped sealing walls 6a, 8b. In view of this arrangement, knocks, which may be incident to handling of the container, will be resisted by the side and top walls of the device 5, so as to protect the seal from damage with resulting leakage of the container contents.

Referring to Figs. 4, 4a, 4b and 5 (wherein parts similar to like parts identified in Figs. 1, 2 and 3, are indicated by the same reference character, respectively) 2x' indicates a pouring spout, preferably of conical shape, its outer end portion being embossed to provide screw threads 10 for the screw threaded side walls 11 of a cap 11a, whereby the cap 11a is conveniently supported on the spout 2x' when the latter is in its reversed position, that is, in inoperative position (Fig. 4a). On the other hand, the cap 11a provides a closure for the spout 2x' when it is in pouring position between pouring operations and therefore reversal of the spout and reassembly of the parts are eliminated after each pouring operation. The inlet end of the spout 2x' is provided with a flange 9 the opposite faces of which are provided with gaskets 9a, 9b. As shown in Fig. 4b, when the spout is disposed in pouring position, its flange 9 is positioned on the wall 6b' and then the closure device 5 is screwed on the collar 4 and tightened until the embossment 5b engages the spout flange and secures it to the wall 6b'. By preference the opening formed by the top wall of the closure member 5 is sized to engage the wall of the spout adjacent its flange 9, so that when the parts are assembled as shown in Fig. 4b, the spout flange 9 is aligned throughout its circumference with the wall 6b' and therefore the spout is axially related to the collar 4.

Following the filling of the container 1, the spout 2x', with cap 11a thereon, is reversed and projected into the container with the gasket 9b seated on the annular wall or seat 6b', next the sealing member 8 is positioned with its sealing element 8b in pressed-in relation with inner walls of the recess 6a to seal the discharge opening through the collar 4, and finally the annular closure device 5 is threaded on the collar 4 and tightened in final position with the embossment 5b engaging the disk 8 under pressure.

As already set forth, the top wall 5a of the closure device is in spaced relation to and spans the sealing elements constituting the walls of the recess 6a and U-shaped element 8b and the marginal portion 5b is embossed inwardly into engagement with the combined sealing and detectable member 8. The embossment 5b and side wall 5c of the device 5 reinforce the top wall 5a, whereby the top wall adequately resists knocks and blows incident to handling without affecting

the relationship of the walls of the recess 6a and element 8b. The inner side wall of the sealing element 8b is of a length to spacedly dispose the member 8 relative to the seat 6b' to accommodate the spout flange 9 and gaskets 9a, 9b, thereon, so that the pressure applied by the embossment 5b on the disk 3 is utilized to secure the spout flange on the seat 6b'.

To effect a pouring operation, the closure device 5 and disk 3 are removed, the spout 2x' is removed and positioned in pouring position on the seat 6b', as shown in Fig. 4b, the device 5 is replaced and tightened so that the embossment 5b engages the gasket 9b under pressure to effect a pressure engagement between the gasket 9a and seat 6b' and finally the cap 11a is removed.

From the foregoing description it is to be noted that provision is made initially to seal the container without the employment of a gasket after the container is filled ready for delivery to a user; that the sealing means are disposed between a deformable member and a collar on the container wall forming the discharge outlet for the container, and mounted within the external closure device 5; and that the external closure device is shaped and arranged to resist externally applied forces without affecting the effectiveness of the sealing means during handling.

It is also to be noted that one element of the sealing means to prevent leakage is capable of deformation and is utilized to detect access to the container contents, so that tampering by an unauthorized person is effectively indicated. As this sealing element consists of a disk and readily positioned, the construction and ease of assembly is simplified.

Figs. 6, 7 and 8 illustrate a modified form of construction wherein separate sealing devices are provided to form an auxiliary seal, these devices also serving to protect the deformable disk against deformation and the sealing means against distortion, due to blows thereon or accidents in handling and transportation of the container and thus eliminate danger of leakage therefrom.

In Figs. 6, 7 and 8, 12 indicates as an entirety a container comprising a body having side walls 12a and a top or head 12b, which may be secured to the side walls 12a as already set forth.

The top 12b is formed with an emptying or discharge opening 13, in which the inner end of a collar 13a is fixedly mounted (as already set forth) adjacent the flange 2' at one side of the top 12b. By preference that portion of the top wall in which the collar 13a is mounted is embossed downwardly and outwardly, as shown at 12b' so that the axis of the collar 13a extends at a right angle to the inclined portion 12b' of the wall 12b. 12x indicates a closure device having an annular top wall 12x', the device 12x being similar in construction to the device 5 hereinbefore referred to.

The side wall of the collar 13a is embossed to provide screw threads, which are engaged by the screw threaded side wall of an annular closure device 12x. The upper end of the collar 13a is provided with an inwardly extending annulus, which, throughout its circumference, is embossed to provide a downwardly extending side wall 15 and an inwardly extending annular support 15a disposed parallel to the embossed wall 12b' to provide a seat for a flange 16 provided on the inlet end of the spout 16a.

17 indicates a combined sealing and deformable member consisting of a removable disk 75

formed of relatively thin resilient material and capable of being deformed, distorted or mutilated. The marginal portion of the disk 17, throughout its circumference, is embossed to provide annular sealing element 17a of U-shape in cross section.

The walls of the sealing element 17a have a pressed-in engagement with the side wall 15 and contiguous portion of the support 15a to effect a tamper-proof seal between the element 17a and wall 15. As the side wall 15 of the collar 13a extends outwardly beyond the peripheral edge of the sealing element 17a, the latter cannot be engaged by a pointed tool or other device and the member 17 pried out, except by deforming the element 17a and/or the member 17, the effect of which is to prevent it from being replaced and used without indicating that access to the container has been made.

The separate sealing devices consist of a removable disk 18 (preferably formed of sheet metal) and a removable gasket 18a. The diameter of the removable disk 18 and outside diameter of the gasket 18a are slightly less than that of the collar 13a. In this form of construction the gasket extends over the sealing element 17a and seats on the deformable disk 17 and upper end of the collar 13a, whereas the disk 18, which is engaged by the top wall 12x' of the closure device 12x, engages the gasket 18a to secure it in position, the latter being seated under pressure when the closure device 12x is tightened in position. By preference, the marginal portion of the disk 18, throughout its circumference, is embossed inwardly, to form an annular shoulder 18b, which fits within the inner periphery of the top wall 12x', whereby, in assembly, the disk 18 is disposed in concentric relation to the side walls of the collar 13a and closure device 12x.

The wall 12x' is embossed inwardly as shown at 12z, whereby the area of the wall 12x' surrounding the embossment 12z is spaced from the disk 18, so that the wall 12x' will initially resist any exteriorly applied force to protect the disk and sealing means against damage or distortion.

The outer side of the flange 16 on the inlet end of the spout 16a is provided with a gasket 19 which is engaged by the deformable disk 17 when the parts are assembled as shown in Fig. 6. As shown, the parts are disposed in superimposed relation so that when the closure device 12x is tightened in position the parts are secured together under pressure and the spout flange 16 is secured to the support 15a and all parts held in fixed relation during handling and transportation.

When the contents of the container 12 are to be discharged or poured, the device 12x is removed, the disk 18 and gasket 18a are discarded, the disk 17 is deformed, removed and discarded, the spout 16a is reversed so that the gasket 19 engages the support 15a and the device 12x is replaced and tightened to secure the spout on the support 15a, as shown in Fig. 8, the gasket 19 serving to prevent leakage or waste between the spout and adjacent parts.

To those skilled in the art to which my invention relates, many changes in construction and widely differing embodiments and applications of the invention will suggest themselves without departing from the spirit and scope of the invention. My disclosures and the description herein are purely illustrative and are not intended to be in any sense limiting.

What I claim is:

1. A container having a discharge opening and

a pouring spout therefor provided at one end with a flange, a closure for said discharge opening consisting of a collar mounted at its inner end therein and provided with screw threaded side walls, the outer end of said collar being provided with an outwardly extending circumferential wall the marginal portion of which provides a support for the flange of said spout, said wall downwardly of its marginal portion being embossed downwardly throughout its circumference to form an annular recess, a removable disk the marginal portion of which is embossed inwardly throughout its circumference to provide an annular wall having a pressed-in engagement with the inner walls of said recess to sealingly close said discharge opening, and an external closure device having an annular top wall and a side wall, said side wall being embossed to provide screw threads thereon removably threaded on the side wall of said collar and said top wall being arranged to removably engage said disk, said disk when engaged by said device serving to secure the flange of said spout on said support.

2. A container having a discharge opening, a reversible pouring spout therefor provided at one end with a circumferential flange, gaskets fixed to the opposite faces of said flange, and a closure for said discharge opening consisting of a collar mounted at its inner end therein and provided with screw threaded side walls, the outer end of said collar being provided with an inwardly extending circumferential wall the marginal portion of which provides a support for the flange of said spout when the latter is in an inoperative position or in a pouring position, said circumferential wall between its marginal portion and said screw threaded side walls being embossed downwardly throughout its circumference to form an annular recess, a removable disk arranged to removably engage the adjacent gasket on the flange of said spout when the latter is in pouring or non-pouring position, the marginal portion of said disk being embossed inwardly throughout its circumference to provide an annular wall having a pressed-in engagement with the inner walls of said recess, and an external closure device having a side wall embossed to provide screw threads thereon removably engaging the screw threads on the side walls of said collar and an annular top wall arranged to engage said disk under pressure when said closure device is positioned on said collar.

3. A closure for a container having a discharge opening consisting of a collar mounted at its inner end therein and provided with a screw threaded side wall, the outer end of said collar being provided with an inwardly extending circumferential wall embossed radially throughout its circumference to form an annular recess of U-shape in cross section, a removable disk for sealingly closing the opening through said collar, formed of relatively thin sheet metal capable of being deformed, the marginal portion of said disk being embossed inwardly throughout its circumference to provide an annular wall of U-shape in cross section having a pressed-in engagement with inner walls of said recess to provide a leak-proof and tamper-proof seal for said discharge opening and an external closure device having a side wall embossed to provide screw threads thereon removably engaging the screw threads on the side wall of said collar, and an annular top the marginal portion of which is embossed

inwardly for engagement with said disk inwardly of its U-shaped embossed walls and providing outwardly thereof an annular wall spaced from said embossed walls.

5 4. A closure for a container having a discharge opening, consisting of a collar mounted at its inner end in said opening and provided with a screw threaded side wall, the upper end of said collar being extended inwardly and embossed radially downwardly throughout its circumference to form within the side wall of said collar an annular recess substantially U-shape in cross section, a removable deformable metallic disk for closing the opening through said collar, the marginal portion of said disk being embossed circumferentially to form an arcuate wall in cross section having pressed-in engagement with the inner wall of said recess to provide a leak-proof and tamper-proof seal for the container, and a closure device having a screw threaded side wall removably engaging the side wall of said collar and a top wall formed with an opening to expose the central portion of said disk.

25 5. A container having a discharge opening, a reversible spout provided at one end with a circumferential flange, a closure for said discharge opening consisting of a collar mounted at its inner end therein and provided with a screw threaded side wall, the outer end of said collar being provided with an inwardly extending circumferential top wall embossed downwardly to provide an inner side wall and terminating in an annular support for the flange of said spout when the latter is in an inoperative position or in a pouring position, a removable deformable disk, the marginal portion of said disk being embossed inwardly throughout its circumference to provide a wall having a pressed-in engagement with said inner side wall and said support, an external closure device having an annular top wall and a side wall, said side wall being embossed to provide screw threads thereon removably engaging the screw threads on the first mentioned side wall of said collar and said disk being arranged to removably engage the flange of said spout, when the latter is in an inoperative position, to secure the flange of said spout on said support, a removable gasket engaging said disk and the top of said collar, and a separate removable disk adapted to be mounted on said gasket and be secured thereto by said annular top wall of said closure device.

40 6. A container as claimed in claim 5 wherein the curvilinear shaped embossed wall of said disk engages said circumferential side wall below its upper end to prevent access to said curvilinear shaped wall.

45 7. A container as claimed in claim 5 wherein the inner marginal portion of the top wall of said closure device is embossed inwardly, whereby said wall outwardly of its embossed portion is spaced from said separate disk.

60 8. A closure as claimed in claim 4 wherein the outer side wall of said annular U-shaped recess extends above said arcuate wall to prevent access to the latter.

HAROLD GAR VAUGHN.
